CLAIM

The ornamental design for a pair of wireless earphones, as shown and described.

DESCRIPTION

FIG. 1 is a front perspective view of a pair of wireless earphones showing our new design;

FIG. 2 is a front view thereof;

FIG. 3 is a rear view thereof;

FIG. 4 is a side view thereof;

FIG. 5 is an opposite side view thereof;

FIG. 6 is a top view thereof; and,

FIG. 7 is a bottom view thereof.

The broken lines are for illustrative purposes only and form no part of the claimed design.
